UNITED STATES PATENT OFFICE.

JOHN ALEXANDER FRISK, OF URBANA, ILLINOIS.

GAS-BURNER AND WATER-HEATER.

1,089,204.

Specification of Letters Patent. Patented Mar. 3, 1914.

Application filed November 5, 1912. Serial No. 728,601.

To all whom it may concern:

Be it known that I, JOHN A. FRISK, a citizen of the United States, and a resident of Urbana, in the county of Champaign and State of Illinois, have invented a new and Improved Gas-Burner and Water-Heater, of which the following is a full, clear, and exact description.

This invention relates generally to a gas burner adapted to also act as a water heater, the structure shown being characterized by an absence of means whereby the passage of air through the burner structure is prevented.

The principal object of the invention is to provide a gas burner and water heater, preferably of integral construction, the embodiment of the invention shown making provision for the utilization of heat below the burner openings as well as along the sides thereof.

One embodiment of the invention is disclosed in the structure illustrated in the accompanying drawings, in which like characters of reference indicate corresponding parts in all the views, and in which—

Figure 1 is a side view showing the burner adapted to an ordinary stove; Fig. 2 is a top plan view of the burner, partly sectional; Fig. 3 is a sectional view on the line 3—3 of Fig. 2; while Fig. 4 is a similar view on line 4—4 of Fig. 2 with the inlet water pipe removed.

The combined burner and heater is especially adapted for use with a supporting structure 1 of any desirable size and form, provided with the usual manifold 2 and gas cock 3, the burner 4 communicating with a reservoir 5 through the pipes 6 and 6^a provided with valves 7 and 7^a.

Referring particularly to Figs. 2, 3 and 4 it will be noted that the burner and heater is substantially of integral construction, circular in outline, and is provided with a number of upstanding walls 8, 9, 10, 11 and 12, the walls 8 and 9, together with the top and bottom portions of the burner, forming a passageway 13, the walls 10 and 11, together with the top and bottom portions of the burner, forming a passageway 14 in communication with the passageway 13 through the intermediate passageway 15. The upstanding wall 12 incloses a passageway 16 having another passageway 17 leading thereto, whereby the circulation of water through all the passageways is provided.

Adjacent the under side of the burner and heater is a chamber 18 provided with the gas inlet 18^a adapted to be connected to the supply of gas, the top wall of the said chamber being provided with a number of burner openings 19; it will be noted that the heat radiated by the burning gas at these openings is prevented from escaping downwardly, being utilized in the heating of water within the passageways, a supply of air to these burners independently of the mixing fluid comprised within the gas cock 3 being unnecessary. There are preferably two circular rows of these burner openings 19, although it is obvious that in the event of making large burners and heaters various numbers of rows of openings may be provided.

Referring particularly to Fig. 3, it will be noted that one side of the burner and heater, that is, the passageway 13 adjacent that side, communicates with the reservoir 5 by means of the pipe 6; it will also be noted that the central chamber 16 of the heater 60 communicates with the reservoir 5 through the lower pipe 6^a and a short pipe 6^b extending through the gas chamber 18 into the said central chamber, the burner structure being 65 preferably provided with threaded openings 70 20, 20^a for the reception of the threaded ends 75 of the said pipes 6 and 6^a. In order to provide for blowing out the heater or cleaning it, the under side is preferably provided with an outlet 21, closed by means of a removable plug 22.

In the use of the device, after the gas has been lighted at the burner openings, the water from the reservoir passes through the lower pipe 6^a, thence through the inner passageway 16, then into the second passageway 14, through the intermediate passageway 17, finally passing into the outer passageway 13 through the passageway 15, then leaving the burner through the pipe entering 90 the threaded shoulder 20 and back to the reservoir. This relative positioning of the pipes for the circulation of the water, together with the particular relation of the passageways among themselves, prevents the 95 burner and heater becoming steam-bound when in use; the maximum amount of heat given by the gas at the burner openings 19 is availed of both in heating material contained in any vessel placed on the burner, 100 and also in heating the water within the burner, since the absence of openings or com-

municating means between the space beneath the burner and that above provides for the absence of drafts which tend to carry away the heated air.

5 In stoves of some size a number of these burners may be used, and they may be connected together to form a battery whereby the water within the reservoir 5 may be heated, the number of burners working at 10 any one time being not dependent on the burners not working at that time.

Having thus described my invention, what I claim as new and desire to secure by Letters Patent is:—

15 1. A gas burner and water heater, comprising a body having a plurality of annular communicating water passages spaced from each other to form annular passages open at the top, the innermost water passages being 20 at the center of the body, a gas chamber on the under side of the body and having in its top burner openings leading into the spaces between the water passages, a water inlet leading into the innermost water passage, 25 and an outlet leading from the outermost water passage.

2. A gas burner and water heater, comprising a body having a plurality of annular communicating water passages spaced from 30 each other to form annular passages open at the top, the innermost water passage being

at the center of the body and communicating with the intermediate passage at a point diametrically opposite the communication between the said intermediate and outermost 35 passages, a gas chamber on the under side of the body and having in its top openings leading into the open top passages, a water inlet leading through the gas chamber and extending into the innermost water passage, 40 and a water outlet leading from one side of the outermost water passage.

3. A gas burner and water heater, comprising a body having a plurality of annular communicating water passages and intervening 45 annular passages open at the top, the innermost water passage being at the center of the body, a gas chamber on the under side of the body and communicating with the open top passages, a water inlet leading through 50 gas chamber into the innermost water passage, a water outlet leading from the side of the outermost water passage, a blow-off opening in the bottom of the outermost passage, and a plug for closing said opening. 55

In testimony whereof I have signed my name to this specification in the presence of two subscribing witnesses.

JOHN ALEXANDER FRISK.
